UNITED STATES PATENT OFFICE.

JAMES R. DONLEY, OF HARTFORD, CONNECTICUT, ASSIGNOR OF ONE-HALF
TO HALSEY B. PHILBRICK, OF SAME PLACE.

SAND-BOX.

SPECIFICATION forming part of Letters Patent No. 603,266, dated May 3, 1898.

Application filed December 4, 1897. Serial No. 660,798. (No model.)

To all whom it may concern:

Be it known that I, JAMES R. DONLEY, a citizen of the United States, residing in Hartford, in the county of Hartford and State of Connecticut, have invented certain new and useful Improvements in Sand-Boxes, of which the following is a specification.

This invention relates to sand-boxes, and more especially to means for obtaining a free flow of the sand to the track and for stopping the supply without the necessity of a valve or analogous cut-off device.

My improved device, which is extremely simple in construction and mode of operation, involves a box or vessel for containing sand, a discharge pipe or tube communicating with the box, and an air-blast pipe leading into said box from a suitable source of supply, such as a tank for containing compressed air to operate the brakes on a locomotive or street-car. When the air-blast is introduced into the sand-box, the sand is loosened up to such an extent as to insure an adequate supply thereof to the track, which is particularly advantageous in wet weather, as under such a condition the sand becomes damp and cannot freely gravitate from a sand-box.

The sand-box may be mounted upon the boiler of a locomotive or suspended from a car-body, and the inlet end of the discharge-pipe will be located above the level of the sand and preferably remote from the bottom of the sand-box, and the air-blast is introduced at a convenient place. When the compressed air strikes the sand in the box, the sand is elevated until it strikes the cover or cap of the box, and as soon as the air is cut off the sand of course drops, and to insure the distribution of an ample quantity of sand to the track the receiving end of the discharge pipe or tube is flared or funnel-shaped, so as to cover a comparatively wide area.

In the drawings accompanying and forming part of this specification, Figure 1 is a front elevation of my improved sand-box suspended from a car-body. Fig. 2 is a longitudinal central section of the same. Fig. 3 is a horizontal sectional plan, the section being taken in the line $x-x$, Fig. 1. Fig. 4 is a longitudinal central section showing the operation of the device and as mounted upon a locomotive-

boiler and two discharge-pipes; and Fig. 5 is a horizontal section taken in line $y-y$, Fig. 4.

Similar characters designate like parts in all the figures of the drawings.

55

My improved track-sanding device involves in its construction a "box," by which is meant any vessel or receptacle suitable for containing sand, and a removable cap or cover for said box, which can be taken from place to place to furnish a supply of sand.

In Fig. 1 the box is designated by B, and its cap or cover by C, the box being secured at regular intervals to the hangers or straps 2, depending from and fixed at their upper ends to a car-body, a portion of which is shown at 3.

The discharge-pipe is designated by D, and it communicates with and leads from the interior of the sand-box B, so as to convey a supply of sand to the track when the sand is acted upon by a blast of compressed air, the sand being elevated above the upper end of the discharge-pipe until it strikes the cap or cover C, and when the air-blast is arrested the sand will drop in a spray into the discharge-pipe. The discharge-pipe D passes through an opening in the bottom or floor of the box B and is held in place by the check-nuts 4 and 5 in threaded engagement with said pipe and abutting against the upper and lower faces of said box-floor.

To insure the collection by the discharge-pipe or conduit D of a relatively large quantity of material on the introduction and subsequent cut-off of the air-blast, the upper end of the discharge-pipe, which is remote from the bottom of the sand-box B, is provided with a flared or funnel-shaped cap 6, the tubular portion of which is sleeved on the discharge-pipe and secured thereto in some convenient manner.

The air-blast pipe is designated by A, and consists of two sections 7 and 8, the first mentioned being annular and the other passing through a wall of the box and communicating with an air-tank. (Not shown.)

The annular pipe-section 7 is provided at regular distances apart with a series of holes or openings 9 on its under side, (see Fig. 3,) through which the blast of air can escape to strike and elevate the sand. The annular

pipe-section 7 rests upon the support 10, having flanges 10' and 10" at its opposite end, fixed to diametrically opposite sides of the sand-box wall, as shown in Figs. 2 and 3, the 5 said pipe-section being held in place against lateral movement by the keepers 12 and 12', secured to the support or bracket 10.

The supply of air to the pipe A from the air-tank is controlled by a valve, (not shown,) 10 which may be operated by an engineer or motorman, and when said valve is opened to admit a current of air to the annular pipe-section the compressed air will pass through the several holes or vents 9 and strike the sand 15 and elevate the latter so long as the air is on. When the blast is stopped, the sand drops and enters the flared or funnel-shaped cap at the upper end of the discharge-pipe D, and passing through the latter will be distributed 20 thereby to the track in the usual manner.

On the removal of the cap or cover C a supply of sand can be emptied into the box B, and I have provided a device for preventing the inflowing sand from entering the discharge-pipe. This device consists, preferably, 25 of a cover 13, adapted to fit over the flared or funnel-shaped cap 6, so as to prevent the entrance of the sand into the discharge-pipe when the box is being filled by an engineer, 30 the cover 13 having a ring 14 by which it may be suspended from the hook 15 on the outside of the sand-box, as indicated in Fig. 1, said cover being connected with the sand-box by the chain 16, so that it cannot be lost.

35 The foregoing description relates to a sand-box which is especially adapted to car-bodies, and in Figs. 4 and 5 I have shown a device intended more especially for application to a locomotive, and in the modified construction 40 two discharge or delivery pipes are provided, they being designated, respectively, by D' and D'', said pipes extending oppositely from the sand-box B' and leading to both tracks. The straight portion of the air-inlet pipe A' communicates with the two annular pipe-sections 45 7' and 7", having the air blast or escape openings on their under sides. The cap or cover C' is in threaded engagement with the sand-box. With this exception the construction

shown in Figs. 4 and 5 is the same as that 50 illustrated in the other views.

Having described my invention, I claim—

1. The combination, with a sand-box, of a discharge-pipe passing through said sand-box and having its inlet located above the level 55 of the sand, and an air-blast pipe leading into said sand-box and having an air-blast opening or openings situated below the inlet end of said discharge-pipe and above the level of the sand.

2. The combination, with a sand-box, of a discharge-pipe passing through and into said sand-box and flared at its upper end, and an air-blast pipe passing through the sand-box and one end surrounding the discharge-pipe, 65 said surrounding portion having one or more air-escape openings.

3. The combination, with a sand-box, of a discharge-pipe passing through the bottom of the sand-box and having a flared inlet end 70 located above the level of the sand, and an air-blast pipe passing through the sand-box and having an annular portion surrounding the discharge-pipe, said annular portion having one or more air-escape openings on its 75 under side.

4. The combination, with a sand-box, of an air-blast pipe, and a sand-discharge pipe the delivery and receiving ends, respectively, of which are situated in the sand-box and are 80 located above the level of the sand.

5. The combination, with a sand-box, of a discharge-pipe communicating therewith and having a flared inlet, a removable cap for covering the inlet of said pipe, a detachable cover 85 for the sand-box, and an air-blast pipe leading into the latter.

6. The combination, with a sand-box, of a discharge-pipe communicating therewith and having a flared inlet above the level of the 90 sand, and an air-blast pipe passing through a wall of the sand-box and having an air-escape opening or openings.

JAMES R. DONLEY.
